[57] CLAIM

The ornamental design for a wiffle ball bat, as shown
and described.

DESCRIPTION

FIG. 1 is a perspective view of a wiffle ball bat;
FIG. 2 is a side elevation view of the bat shown in FIG.
1; all side elevation views being identical;
FIG. 3 is an end view of the bat shown in FIG. 1 taken
from the left hand side of the bat shown in FIG. 1; and,
FIG. 4 is an end view of the bat shown in FIG. 1 taken
from the right hand side of the bat shown in FIG. 1.

Fig. 4
